TRUCK CAB

Theodore J. Zeller, Allentown, Pa., assignor, by mesne assignments, to Mack Trucks, Inc., a corporation of New York

Application August 2, 1955, Serial No. 37,278

Term of patent 14 years

(Cl. D14—3)

FIG.1.

FIG.2.

FIG.3.

FIG.4.

Fig. 1 is a view in front elevation of a truck cab embodying my new design;

Fig. 2 is a side elevational view thereof;

The broken line portions are shown for convenience of illustration only.

I claim:

The ornamental design for a truck cab, as shown and described.
